WRENCH

Roy E. Gearhart, Kansas City, Mo., assignor of three-tenths to Byram L. McCreary and three-tenths to Richard B. McCreary, both of Kansas City, Mo.

Application June 28, 1943, Serial No. 492,639

8 Claims. (Cl. 81—87)

This invention relates to improvements in a wrench and has particular reference to a wrench having a double action whereby the wrench jaws are constantly urged toward each other during the operation on a nut or screw.

This invention is an improvement over my invention set forth in application, Serial No. 490,106 and has for its principal object the provision of a jaw operating structure having double means whereby the jaws are moved through a relatively long distance during the nut engaging operation.

Another object of this invention is the provision of a wrench having a pair of relatively adjustable jaws, an adjustable fulcrum, a toggle anchored to said fulcrum and including a lever having an operating cam whereby as said lever is oscillated, both the toggle structure and the lever cam will simultaneously cause said jaws to move toward or from each other.

Other objects are sturdiness and economy of construction, speed and efficiency of operation and adaptability for operating a nut or screw through a relatively short arc without removing the wrench from its position about said nut or screw.

Reference will now be had to the drawing, wherein:

Figure 1 is an edge view of a wrench positioned to engage a nut and embodying this invention.

Fig. 2 is a plan view of the wrench as shown in Fig. 1.

Fig. 3 is a sectional view taken on line III—III of Fig. 1 with the jaws moved to the gripping position.

Fig. 4 is a sectional view taken on line IV—IV of Fig. 2.

Fig. 5 is a sectional view taken on line V—V of Fig. 2.

Fig. 6 is a fragmentary sectional view of a modified form of the wrench wherein a cam is formed on the sliding yoke to cooperate with end of the operating lever.

Throughout the several views like reference characters refer to similar parts and the numeral 10 designates a shank or handle having a fixed jaw 12 in which is formed an angled groove 14 to form nut engaging faces 16 suitable for simultaneously engaging adjacent sides of a nut or screw for setting or removing the same.

Slidably mounted on shank 10 is a yoke or block 18 having a jaw 20 complementing jaw 12. This jaw is grooved at 22 to present nut engaging surfaces 24. Referring to the drawing, it will be noted that the nut engaging surfaces are so positioned as to properly engage a hexagon nut.

However, it is desired that the angled relation of these engaging surfaces may be varied to engage the various shaped nuts and might in some instances be provided with cutting blades suitable for severing metal or other materials. The angled relation of the jaws 12 and 20 to the body of the shank is shown at right angles to the lever movement but may be varied as shown in Fig. 6 in alignment therewith.

10 The yoke 18 is recessed at 26 to present side walls 28 between which is fitted the inner end of lever 30. This lever is provided adjacent its inner end with a transverse pin 32 which is slidably mounted in slots 34 formed in side walls 28. These slots 34 are disposed parallel with shank 10. The inner end portion of lever 30 is offset to form a cam 36. This cam operatively engages in a groove 38 formed in yoke 18 as clearly shown in Fig. 3.

20 Referring to Fig. 2, it will be noted that the end portion 40 of lever 30 engages the abutment 42 when the lever is in the fully extended position as shown. However, when the lever is moved inwardly toward shank 10 then end portion 40 will

25 recede from abutment 42 as the cam 36 engages the inner portion 44 of said abutment to move the pin 32 along slot 34. The lever 30 is normally secured in the extended position by means of a tension spring 46 which is secured to said lever by means of a screw 48 with its inner end resting against a fulcrum member 50. After the lever 30 has been moved to the position shown in Fig. 3 by gripping the shank and lever, the lever may be returned to its normal position by the action of spring 46 by releasing the hand grip on the wrench and as the lever moves away from shank 18 cam 36 will engage lug 52 to return yoke 18 to its normal position.

30 The fulcrum member 50 is of elongated bar form having a series of teeth 54 and is secured for limited longitudinal movement between walls 28 by means of a pin 56 which is fixed to the member 50 with its ends protruding at each side thereof for sliding engagement in slots 58 formed in side walls 28 in parallel relation with shank 10. It will be noted that the ratchet teeth 54 are spaced longitudinally of the bar from the pin 56 so as to permit the hinging of the bar on the pin to free teeth 54 from the rachet bar teeth 60 formed on the inner face of shank 10.

35 It is preferable to make teeth 54 and 60 in ratchet form angled to prevent relative slippage therebetween when the jaws are being forced against the nut and to permit easy ratcheting movement of the teeth when the jaws are being

moved toward each other during the initial setting of the wrench.

Links 62 at each side of the lever 30 are pivoted thereto by a pivot 64 while the other ends of said links are connected by pivot 66 to the outer end of fulcrum member 50 so that when the member 50 is in the position shown in Fig. 2, the teeth on the fulcrum bar member will engage the teeth of the rack bar 60 to prevent relative longitudinal movement of the fulcrum member and shank.

When the wrench parts are in the position just described and as shown in Fig. 2 with the pin 32, pivot 64 and pivot 66 in offset angled relation to present a toggle, the operator, by pressing lever 30 toward shank 10, will cause the jaws to be moved to engage nut N. It will be noted that there is a double action, the first action tending to move the jaws toward each other being produced by the toggle action which tends to move the pivotal points of the toggle nearer a straight line, the other action being the cam action against the abutment wall 42. While for illustrative purposes the relative lever advantages between the toggle action and the cam action have been shown in favor of the toggle action, however, if desired, the relative lever action might be reversed or made to conform to any desired proportion without departing from the spirit of this invention.

When it is desired to adjust the wrench to fit a nut smaller than the nut previously operated, the operator simply forces the lever 30 forwardly and the teeth 54 on fulcrum member 50 slide over ratchet teeth 60 to the proper position. However, when the nut to be operated on is larger than the nut previously operated on, it is necessary to raise the fulcrum member 50 against the action of spring 46 a sufficient distance to release the teeth 54 from the rack teeth 60 and pull the lever 30 along shank 10 to separate the jaws the proper distance. One of the material advantages obtained by the provision of the relatively long adjustment of jaw 20 is the fact that the wrench may be maintained in position about the nut as shown in Fig. 2 so that the jaws will be sufficiently spaced apart to permit the movement of the wrench about the nut to obtain a new grip thereon when the lever is in the open position. This facilitates much more rapid operation than could be obtained were it necessary to raise the wrench from the nut to turn it to the new gripping position. If it is desired to have a shorter movement of the lever 30 relative to shank 10, then the operator may move the fulcrum member 50 inwardly one tooth, thereby setting the jaws closer together so that the necessary relative movement of the jaws to clamp the nut will be lessened.

Referring to Fig. 1, it will be noted that the inner portions of jaws 12 and 20 are serrated at 68. These serrations do not interfere with the nut engaging surfaces and may be useful in removing studs and operating on pipes, etc.

In Fig. 6, showing a modified form of the wrench, it will be noted that a cam surface 70 is formed on abutment 72 which is integral with yoke 74. Lever 76 is provided at its inner end with an arcuate surface 78 which is normally out of engagement with cam 70 when the lever is in the open position as shown, but which contacts cam 70 when the lever is moved toward shank 10. The jaws 82 are shown in longitudinal alignment with the lever 76 and when the parts are so positioned, it is quite apparent that the line of push against jaw 82 will be substantially a

straight line, thereby insuring a very efficient gripping means. The general construction of this modified form is the same as that of the preferred form.

From the foregoing it will be understood that various alterations in the details of construction and arrangement of the parts may be made within the scope of the invention herein disclosed and claimed.

What I claim is:

1. A wrench comprising a shank having a fixed jaw, a yoke slidably carried by said shank and having a jaw complementing said fixed jaw, a hand operable toggle means pivotally carried by said shank and slidably carried by said yoke adapted to force said jaws toward and from each other, and a cam integral with said toggle means and engaging said yoke operable by said toggle means to force said jaws toward and from each other.

2. A wrench comprising a shank having a fixed jaw, a yoke slidably mounted on said shank and having a jaw complementing said fixed jaw, a fulcrum adjustably secured to said shank, a lever having its one end slidably mounted in said yoke and being pivotally connected by links pivoted to said fulcrum whereby as said lever is moved toward said shank the jaws will be moved toward each other, and a cam engaging said yoke and rigid with said lever operable as said lever is moved relative to said shank to force said jaws toward or from each other.

3. A wrench comprising a shank having a fixed jaw, a yoke slidably mounted on said shank and having a jaw complementing said fixed jaw, a fulcrum adjustably secured to said shank, a lever having its one end slidably mounted in said yoke and being pivotally connected by links pivoted to said fulcrum whereby as said lever is moved toward said shank the jaws will be moved toward each other, and cam means interconnecting said lever and yoke operable as said lever is moved toward said shank to force said complementing jaw away from said fulcrum.

4. A wrench comprising a shank having a fixed jaw, a yoke slidably mounted on said shank and having a jaw complementing said fixed jaw, a lever having its inner end slidably carried by said yoke, a fulcrum member adjustably secured to said shank with its inner end longitudinally slidably mounted in said yoke and being pivotally connected by a link to said lever whereby as said lever is moved toward said shank said jaws will be moved toward each other, and a cam rigid with said lever and engaging said yoke operable as said lever is moved toward said shank, to urge said jaws toward each other.

5. A wrench comprising a shank having a fixed jaw, a yoke slidably mounted on said shank and having a jaw complementing said fixed jaw, a lever having its inner end slidably carried by said yoke, a fulcrum member adjustably secured to said shank with its inner end longitudinally slidably mounted in said yoke and being pivotally connected by a link to said lever whereby as said lever is moved toward said shank said jaws will be moved toward each other, and a cam carried by said lever and engaging said yoke operable as said lever is moved toward said shank, to urge said jaws toward each other.

6. A wrench comprising a shank having a fixed jaw, a yoke slidably mounted on said shank and having a jaw complementing said fixed jaw, a lever having its inner end slidably carried by said yoke, a fulcrum member having teeth adapted to

engage teeth formed in the adjacent face of said shank, adjustably secured to said shank with its inner end longitudinally slidably mounted in said yoke and being pivotally connected by a link to said lever whereby as said lever is moved toward said shank said jaws will be moved toward each other, and a cam rigid with said lever and engaging said yoke operable as said lever is moved toward said shank, to urge said jaws toward each other.

7. A wrench comprising a shank having a fixed jaw, a yoke slidably mounted on said shank and having a jaw complementing said fixed jaw, a lever having its inner end slidably carried by said yoke, a fulcrum member adjustably secured to said shank with its inner end longitudinally slidably mounted in said yoke and being pivotally connected by a link to said lever whereby as said lever is moved toward said shank said jaws will be moved toward each other, and a cam rigid

with said lever operable as said lever and engaging with said yoke is moved toward said shank, to urge said jaws toward each other.

8. A wrench comprising a shank having a fixed jaw, a yoke slidably mounted on said shank and having a jaw complementing said fixed jaw, a lever having its inner end slidably carried by said yoke, a fulcrum member adjustably secured to said shank with its inner end pivotally mounted for limited longitudinal movement in said yoke and being pivotally connected by a link to said lever whereby as said lever is moved toward said shank said jaws will be moved toward each other, and a cam rigid with said lever and engaging a surface of said yoke inclined to the path of travel of said yoke operable as said lever is moved toward said shank, to urge said jaws toward each other.

20

ROY E. GEARHART.
